UNITED STATES PATENT OFFICE.

CARL RUDER, OF WANDSBEK, GERMANY.

PROCESS OF PRODUCING A MIXTURE OF CAMPHENE AND ISOBOURNYL ACETATE FROM PINENE HYDROCHLORID.

1,105,378.

Specification of Letters Patent.

Patented July 28, 1914.

No Drawing.

Application filed February 13, 1913. Serial No. 748,154.

To all whom it may concern:

Be it known that I, CARL RUDER, doctor of philosophy, manufacturer, a subject of the King of Bavaria, residing at Wandsbek, 5 near Hamburg, in the State of Prussia, German Empire, have invented certain new and useful improvements in an Improved Process of Producing a Mixture of Camphene and Isobornyl Acetate from Pinene Hydrochlorid, of which the following is a specification.

It has already been proposed to remove the chlorin from pinene hydrochlorid by heating it with acetate of lead in the presence of glacial acetic acid. This process, however, has proved itself completely unsatisfactory and impractical, as the reaction is not even approximately quantitative. Even after heating pinene hydrochlorid for 20 sixty hours with acetate of lead a product free from chlorin is not obtained. Further it is a well known fact that pinene hydrochlorid, by heating it with fatty acids and zinc salts of fatty acids, yields camphene and 25 the iso-bornyl ester of the fatty acid. A great disadvantage of this process, however, is that the formation of zinc chlorid results in the condensation of much of the terpene compounds and consequently in very unsatisfactory yields. This objectionable condensing effect of zinc chlorid becomes particularly noticeable when distilling off the fatty acid which has been used, so that it is practically impossible to recover the fatty 30 acid. The oily mixture herein set forth is to be considered as the substantial equivalent of pinene hydrochlorid. This detrimental effect of zinc chlorid may be avoided by adding to the mixture a second salt of the 35 corresponding fatty acid, which reacts with the zinc chlorid present, forming the corresponding metallic chlorid, and regenerating the corresponding zinc salt of the fatty acid. Instead of a salt of a fatty acid, metallic 40 oxid, for instance oxid of lead, may be used for the same purpose.

Experiments have shown that the chlorid of zinc which forms during the reaction is necessary in order to effect a complete removal of the chlorin. If for instance, the whole quantity of the fatty acid salt is added at once, in spite of heating the mixture for a prolonged period, it is impossible to obtain a product free from chlorin. As, therefore,

the presence of zinc chlorid is necessary in 55 order to effect the removal of the chlorin it is preferable to effect the same first and then add the second salt of the corresponding fatty acid, which renders the zinc chlorid harmless. After stirring the mixture for a 60 short time, the surplus fatty acid may be distilled off without affecting or impairing the yield in any way. The zinc chlorid which forms during the reaction also, to some extent, exerts a condensing effect. 65 In order to prevent this condensing action a portion—about half of the required quantity—of the fatty acid salt may be added immediately at the commencement of the dechlorination process, whereas the remainder 70 of said salt is added after the reaction is completed. The duration of the reaction under such circumstances is only slightly prolonged, while the yield becomes much more satisfactory.

75 The sodium, potassium and lead salts of fatty acids form the most suitable addition since accompanied by the re-formation of the corresponding zinc salt, sodium chlorid, potassium chlorid, and lead chlorid respectively are formed, none of which have any condensing properties.

It is immaterial whether the metallic oxides or the formed (fatty acid) salts—the latter either hydrated or anhydrous—are 85 employed, as only the duration of the process is varied in this way.

The product from which the chlorin has been removed consists of a mixture of camphene and iso-bornyl ester of the fatty acid. 90 It is perfectly free from condensation products and is eminently suitable for the production of the iso-bornyl ester of the fatty acid.

Example.

95

(1) 172 parts of pinene hydrochlorid are heated with 120 parts of anhydrous zinc acetate and 500 parts of glacial acetic acid, for 4 hours to a temperature of 100° C. 100 while being stirred, 98 parts of potassium acetate are then added and the glacial acetic acid is distilled off. The residue is washed with water, the result being a mixture of camphene and iso-bornyl ester which is perfectly free from chlorin.

(2) 172 parts of pinene hydrochlorid, 45 parts of oxid of zinc, 40 parts of fused

acetate of sodium and 500 parts of glacial acetic acid, are heated with stirring to boiling, for 10 to 12 hours under a reflux condenser, a further 42 parts of fused sodium acetate are then added and the whole stirred for another half an hour. The mixture is allowed to stand over night; the layer of terpene salted out by the sodium chloride formed by the reaction is removed and 10 washed free from acetic acid. The glacial acetic acid and zinc acetate mixture is again ready for use after the sodium chloride has been filtered off.

(3) 172 parts of pinene hydrochlorid with 15 50 parts of zinc oxide and 500 parts of glacial acetic acid are heated to boiling for 4 hours under a reflux condenser, 163 parts of anhydrous lead acetate are then added and the glacial acetic acid is distilled off, 20 the mixture being stirred meanwhile. The residue is treated with water and the oily mixture, which is perfectly free from chlorin, is removed from the aqueous solution. This solution after filtering off the 25 lead chlorid is evaporated to dryness, and the zinc acetate is thus recovered ready for use.

(4) 172 parts of pinene hydrochlorid are 30 heated with 120 parts of anhydrous zinc acetate and 500 parts of glacial acetic acid for four hours to 100° C. with constant stirring; 112 parts of oxid of lead are then added and the glacial acetic acid is distilled off the mixture being stirred during the 35 distillation. The further treatment is similar to that described in Example 3.

Instead of acetic acid and the acetic salt,

any other fatty acid or its salts may of course be employed.

I claim:

1. An improved process for producing a mixture of camphene, and the isobornyl ester of a fatty acid from pinene hydrochlorid consisting in heating the same with a fatty acid and the zinc salt of a fatty 45 acid to effect the removal of the chlorin and adding a quantity of another salt of the corresponding fatty acid of a metal whose chlorid has no condensing action on the terpene compounds, whereby all the zinc 50 chlorid formed during the re-action is converted into the zinc salt of the fatty acid with the formation of the corresponding chlorid of the added metal.

2. An improved process for producing a 55 mixture of camphene and iso-bornyl acetate from pinene hydrochlorid consisting in heating the same with acetic acid, zinc acetate, and the acetate of a metal whose chlorid has no condensing action on the 60 terpene compounds, a portion of the latter salt being added before the commencement of the de-chlorination, and the remainder after the completion of the same so that the necessary quantity of zinc chlorid required for the reaction may be present in the mixture during reaction.

In testimony whereof I affix my signature in presence of two witnesses.

DR. CARL RUDER.

Witnesses:

ERNEST H. L. MUMMENHOFF,
IDA CHRIST. HAERMANN.
